SEPARATING MACHINE

John Quirk Sherman, deceased, late of Dayton, Ohio, by Katherine M. Sherman, William C. Sherman, and Wellmore B. Turner, executors, all of Dayton, Ohio

Original application April 5, 1935, Serial No. 14,854. Divided and this application August 1, 1941, Serial No. 405,094

28 Claims. (Cl. 271—2.1)

This invention relates to assorting apparatus for manifolding material, and more particularly to a method of operation and mechanism for progressively separating alternating continuous interfolded strips of record and transfer material, and rearranging the separated strips into individual packets.

The use of continuous superposed strips of series connected forms interleaved with continuous strips of "one time" carbon material for production of manifold copies of written material has become quite extensive and common as a time saving expedient. Heretofore it has been the usual practice to collectively divide the strips transversely into successive sets of forms and interleaved sheets of transfer material which must be subsequently manually separated and assorted according to destination or use of the several copies. Much time of assembling and inserting the material in the writing machine is saved by the use of such continuous series connected forms, but, subsequently considerable time is consumed in the manual separation of detached sets of forms and transfer material.

The present invention provides for high speed mechanical separation of the inscribed strips of connected forms and the interleaved transfer material, thus achieving a great saving in time and affording increased efficiency. Instead of distributing the separated copies of successive sets of forms as heretofore, the present method and apparatus enables consecutive copies of different sets of forms to be kept together by refolding the separated strips without dividing them into independent sheets or form portions. Thus, in a typical system wherein duplicate copies of each order are to be forwarded respectively to the warehouse, the packing department, the delivery department, sales department, accounting department, and a customer's copy enclosed with each shipment, by the present apparatus and method of separating the superposed inscribed record strips into separate packets, copies for each department or purpose are kept in consecutive order, whereby they are more easily handled, assured against loss or misplacement, and much time of the typist is saved.

The present is a division of copending application Serial No. 14,854, filed April 5, 1935, now matured into Letters Patent No. 2,275,475, to the filing date of which the present application is entitled, wherein generic claims to the present disclosure are contained, and to which reference is made for further disclosure of this and analogous apparatus and method. The instant mat-

ter pertains to a distinctive species of strip separating apparatus, wherein the assembly of alternating superposed record and transfer strips withdrawn from a single supply packet wherein the plural strips are collectively interfolded, and are divergently directed through radiating paths of travel into individual receivers wherein the strips are reformed into individual zigzag folded packets. To facilitate the refolding of the strips in their respective receiving compartments, and incidentally to break any adhesion of the strips one to another, a vibratory motion is transmitted to the strips during their advancement from the common supply pack to the receiving compartments.

The separating apparatus may be associated directly with a writing machine whereby the strips are immediately separated as they pass from such writing machine. Such apparatus preferably comprises a separate motor driven unit to which the inscribed manifolding material is transferred from the writing machine. In the event the material is marginally punched for pin wheel feeding devices, the separating apparatus may be provided with a pin type roller, the feeding pins of which engage in the marginally punched feed holes. It is found, however, that due to the interfolding of the several strips, by applying traction to a single interleaved transfer strip or to only one of the record strips all of the associated interfolded strips may be drawn in unison from the supply packet without other feeding means.

The object of the invention is to provide an assorting or separating apparatus for disassembling superposed interfolded strips of manifolding material which may be economically constructed and operated and which will be efficient and rapid in use, substantially automatic in action, and unlikely to get out of repair.

A further object of the invention is to enable separate distribution of multiple copy inscribed forms, whereby corresponding copies of successive sets of forms will be maintained in interconnected sequence.

A further object of the invention is to provide an improved apparatus and method of operation by which collectively interfolded strips of record and transfer material may be progressively separated and reformed into individual packets.

A further but no less important feature of the invention is the provision of vibrating means by which to and fro vibratory motion is transmitted to the strips during their advancement from the supply packet into individual packets.

A further object of the invention is to provide a strip separating apparatus having the advantageous structural features and inherent meritorious characteristics and mode of operation herein mentioned.

With the above primary and other incidental objects in view as will more fully appear in the specification, the invention intended to be protected by Letters Patent consists of the features of construction, the parts and combinations thereof, and the mode of operation, or their equivalents, as hereinafter described or illustrated in the accompanying drawing.

In the drawing,

Fig. 1 is a perspective view of an assembled strip separating apparatus embodying the present invention.

Fig. 2 is a detail view of the vibratory strip guiding device.

Like parts are indicated by similar characters of reference throughout the several views.

While the present separating and strip assorting apparatus may be directly associated with a writing or imprinting mechanism, by the strip feeding devices of which the assembly of superposed strips may be delivered directly to the present separating apparatus, it is preferably embodied in a separate self-contained unit. While the separator illustrated in the drawing is effective and efficient for the present purpose, it is to be understood that it is obviously not the only form of embodiment of the invention but comprises only one species thereof, and therefore the invention is not limited to the specific structure shown. Likewise, while manifolding assemblies to be separated usually comprise superposed record strips and interleaved transfer strips of "one time" carbon material, they are not necessarily so arranged, but may comprise record strips exclusively, either carbon backed or those utilized with sheets of carbon stationarily interleaved between the strips at the record receiving position, past which the strips will have been advanced.

Referring to Fig. 1, the present unit includes a main frame or supporting structure 1 which arises from a base 2. Located at the top of the structure is a box or compartment 3 for a supply packet 4 of interfolded plural strips 5 to be separated. Adjacent to the supply compartment and connected thereto by a guide passage or trough 6 is a strip feeding device common to all the strips of the assembly. The feeding device may be of any desired type, either frictional or positive. That illustrated comprises a roller 7 having therein radial feeding pins 8 engageable in marginally punched holes 9 of the superposed strips 5. Coacting with the roller 7 to guide the strip assembly from the guide passage 6 to the guide panels 11, and thence to individual strip receivers, are slotted strip guide fingers 8' between which and the roller 7 and the strip assembly is advanced by the feeding pins 8. It is not essential that the feed device directly engage all of the strips of the assembly, since the interlocking folds of the collectively folded strips in the supply packet and the inherent friction between the strips is sufficient to cause the strips to be advanced in unison even though only one or a portion of the strips be positively fed by the feeding device. While ordinarily the feeding device is actuated by an electric motor, for illustrative purposes an actuating crank handle 18 is shown for manual actuation. Extending

downwardly from the feeding device in radi-

ating or divergent relation are a plurality of guide panels 11, one for each strip. By means of the angularly disposed guide panels 11 the several strips are directed into divergent paths as they leave the feeding device.

Located on the base 2 is a plurality of strip receivers or collecting compartments 12. Disposed in elevated relation above the base and receivers 12 is a second series of shelf-like receivers or strip compartments 13. The latter are disposed in staggered or offset relation with the receivers 12 of the first series. The receivers 12 and 13 are positioned to separately receive the several strips. Those strips destined for the lower series of receiving compartments 12 pass intermediate or beyond the compartments 13 of the upper series.

Mounted upon the frame or supporting structure 1 is vibratory frame 14, from which project relatively spaced pairs of parallel guide pins 15 which extend through slots 16 in the frame 1 of sufficient size to permit an ample range of to and fro motion. The parallel spaced pins 15 form guides for the several strips of the manifolding assembly intermediate the ends of the divergent guide panels 11 and the receiving compartments 12 and 13.

The assembly of superposed strips 5 are collectively withdrawn from the supply packet 4 within the elevated compartment 3, or may be supplied directly to the present unit from the writing or imprinting apparatus. They are advanced in unison over the guide 6 and thence over the feeding roller 7 beyond which they are separated and directed through separate paths in angularly inclined or divergent relation relative to each other by a series of radiating guide panels 11. Beyond the ends of the guide chutes the strips pass between the corresponding guide pins 15 to the corresponding receiving compartments 12 and 13, wherein they automatically reassume zigzag reversely folded formation upon the original fold lines of the supply packet 4. The pairs of spaced pins 15 between which individual strips are directed are also effective to determine the divergent paths of the several strips.

To insure automatic refolding of the separated strips upon their original fold lines, the frame 14 and guide pins 15 carried thereby are given a to and fro reciprocatory motion which is transmitted to the several strips passing intermediate the guide pins. Such motion serves to lay the strip first in one direction and then in the other in succeeding folds. This insures free uniform refolding of the strips at a comparatively rapid rate without danger of disarrangement or tearing of the forms.

To impart vibratory motion to the frame 14 and advancing strips 5, the frame 14 is connected by a link 17 with a crank or wrist pin 18 upon a disc 19 carried by the feed roller shaft and rotating in unison with the feed roller 7. The link 17 being suitably connected at its opposite end to the reciprocating frame 14 by a bell crank lever 20 transmits to and from motion to the guide pin carrying frame 14.

As the feeding roller 7 is rotated to progressively advance the several strips from the supply packet 4 to the individual receiving compartments 12 and 13, the guide frame 14 is reciprocated to and fro to impart to the strips alternating impulses in opposite directions, which not only break any adhesions of the strips, but simultaneously facilitate the refolding of the

separated strips upon their original fold lines. While the feeding roller 1 has been shown provided with feeding pins 8 engageable in marginally punched holes 9 in one or more of the strips 5, for positively feeding the assembly of strips from the supply compartment 3 to the receiving compartments 12 and 13, it is to be understood that a frictional feeding device may be used in lieu thereof, as is illustrated in the parent case, in which event the strips need not be marginally punched.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute, the invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended claims.

Having thus described the invention, what is claimed is:

1. A separating apparatus for an assembly of superposed strips, at least a portion of which have therein longitudinally spaced feed holes, a frame, a pin type feeding device at the top of the frame for engagement in the said feed holes for collectively advancing the strips in unison from a source of supply, a support over which the strips are progressively advanced, multiple pairs of guide elements located below the level of the pin type feeding device, between the members of the respective pairs of which individual strips are advanced divergently from the support, and receivers into which the individual strips are delivered from the respective pairs of guide elements.

2. A separating apparatus for an assembly of superposed strips, at least a portion of which have therein longitudinally spaced feed holes, a frame, a pin type feeding device at the top of the frame for engagement in the said feed holes for collectively advancing the strips in unison from a source of supply, a support over which the strips are progressively advanced, a plurality of downwardly directed radially disposed guides for individual strips of the assembly to which the strips are delivered by said pin type feeding device, and a plurality of receivers into which the several strips are independently delivered from said radially disposed guides.

3. A separating apparatus for an assembly of superposed strips, at least a portion of which have therein longitudinally spaced feed holes, a frame, a pin type feeding device at the top of the frame for engagement in the said feed holes for collectively advancing the strips in unison from a source of supply, a support over which the strips are progressively advanced, a plurality of relatively spaced guide devices located below the level of said support to which the strips are individually directed downwardly from the common support through radiating paths of travel, and separate receivers for the individual

strips associated with the respective guide devices.

4. In an apparatus for separating multiple superposed strips, a feeding device engageable with at least one of the strips for advancing the plurality of strips in unison from a source of supply, a series of guides for individual strips of the plurality, a plurality of receivers associated with the respective guides into which the strips are simultaneously advanced past the respective individual strip guides by the operation of the feeding device, and means for transmitting vibratory motion to the guides during the passage of the strips to facilitate folding of the strips in the receivers.

5. In a strip separating apparatus, a supporting frame, a strip feeding device thereon common to a plurality of superposed strips to be separated, a series of radiating strip guides relative to which the strips are individually advanced by the common feeding device, and a plurality of receivers into which certain of the strips are individually delivered from the guides.

6. In a strip separating apparatus, a supporting frame, a strip feeding device thereon common to a plurality of strips to be separated, a plurality of strip guides disposed to individually guide the strips in divergent paths of travel relative to which the strips are advanced by the common strip feeding device, and a plurality of receivers, into which different strips are divergently directed by the guides.

7. In a strip separating apparatus, the combination with a strip feeding device common to a plurality of superposed continuous strips to be separated, of a series of spaced strip guides relative to which the strips are progressively advanced in downwardly divergent directions, and a plurality of receivers into which certain of the strips are individually delivered from said guides.

8. In a strip separating apparatus wherein strips of a collective packet are individually deposited into separate receivers, a strip feeding device common to a plurality of strips, separate receivers for individual strips to which the strips are simultaneously delivered, and means for imparting a succession of vibratory impulses to the strips intermediate the strip feeding device and the receivers.

9. In a strip separating apparatus wherein strips of a collective packet are individually deposited into separate receivers, a strip feeding device common to a plurality of strips, separate receivers for individual strips to which the strips are simultaneously delivered, and vibratory means for agitating the strips during their advancement by the strip feeding device.

10. In a strip separating apparatus wherein strips of a collective packet are individually deposited into separate receivers, a strip feeding device common to a plurality of strips, separate receivers for individual strips to which the strips are simultaneously delivered, and impulse transmitting means for effecting a jogging effect upon the advancing strips.

11. In a strip separating apparatus wherein strips of a collective packet are individually deposited into separate receivers, a strip feeding device common to a plurality of strips, separate receivers for individual strips to which the strips are simultaneously delivered, and a beater member repetitiously engaging a plurality of the strips beyond the feeding device.

12. A strip separating apparatus wherein an assembly of superposed independent strips are separated from each other, a strip feeding means common to the assembly of strips and operative to advance the strips in unison, a plurality of guides for the individual strips relative to which the strips are individually advanced, and means for transmitting a succession of vibratory impulses to the strips during their approach to the individual guides.

13. In a strip separating apparatus, a strip feeding device for collectively advancing a plurality of strips past a separation point, a plurality of separate receivers for the separated strips, guide means for directing separated strips to individual receivers, and a beater device for imparting to the strips a percussion action during advancement thereof.

14. In a strip separating apparatus, a strip feeding device for collectively advancing a plurality of strips past a separation point, a plurality of separate receivers for the separated strips, guide means for directing separated strips to individual receivers, and a shock imparting device effective to impart vibratory motion to the strips as they are advanced by the strip feeding device.

15. The herein described method of separating a manifolding assembly of continuous alternating strips of record and transfer material, including advancing the assembly of strips in unison past a separation point, separately directing different strips of the assembly through separate paths of travel, transmitting vibratory motion to the strips during advancement thereof, and collecting the separately directed strips into separate portions.

16. The herein described method of separating a unitary packet of interfolded superposed continuous alternating record and transfer strips into plural packets, including advancing the superposed strips in unison from the initial packet, directing different strips thereof through separate paths of travel, shaking the strips during advancement thereof and refolding the separated strips of the initial single packet into a plurality of packets.

17. A strip separating apparatus, including a supporting structure, a strip feeding device for advancing in unison a plurality of superposed strips past a separating position, and an agitator for the strips actuated in unison with the strip feeding device operative upon the strips during their advancement.

18. A strip separating apparatus, including a supporting structure, a strip feeding device for advancing in unison a plurality of superposed strips past a separating position, and an agitator imparting to the strips alternating movement perpendicular to the planes of the strips during their advancement.

19. A strip feeding apparatus, wherein a packet of collectively assembled superposed strips are separated into independent packets, a strip feeding device for advancing a plurality of such strips to a separation point, a plurality of inclined spaced guides relative to which different strips of the plurality are advanced and a plurality of spaced strip receivers disposed in vertically spaced relation one above another, to which different strips of the plurality are directed by the guides.

20. A strip feeding apparatus, wherein a packet of collectively assembled superposed strips are separated into independent packets, a strip feed-

ing device for advancing a plurality of such strips to a separation point, a plurality of spaced guides relative to which different strips of the plurality are advanced, and a plurality of spaced strip receivers disposed in vertically spaced relation one above another, to which different strips of the plurality are directed by the guides.

21. A strip feeding apparatus, wherein a packet of collectively assembled superposed strips are separated into independent packets,

10 a strip feeding device for effecting simultaneous advancement of a plurality of such strips, guide means for directing the strips in relatively inclined paths of travel, and a plurality of spaced receivers into which different strips are deposited.

22. In a strip separating apparatus, a plurality of strip guides relative to which different strips pass downwardly from a collective assembly thereof, a plurality of receiving compartments to which certain of the strips are directed by said guide chutes, and strip folding means for causing certain of the strips to be folded in zigzag packs in the receiving compartments.

23. In a strip separating apparatus, a plurality of guide chutes relative to which different strips pass downwardly from a collective assembly thereof, receiving compartments arranged in superposed spaced relation into which certain of the strips are directed by the guide chutes, and strip folding means for causing certain of the strips to be folded in zigzag formation within the compartments.

24. In a strip separating apparatus, a plurality of guide chutes, relative to which different strips pass downwardly from a collective assembly thereof, a plurality of receivers, one for each guide chute to which the strips are directed thereby, and spaced strip guides adjacent to the guide chute entrances for guiding different strips to corresponding guide chutes.

25. In a strip separating apparatus, a plurality of guides arranged side by side relative to which different strips pass downwardly from an assembly thereof, receivers to which different strips are directed by corresponding guides, a support for a supply pack of collectively assembled strips to be separated at one side of the entrance to said guides, a strip assembly guide relative to which the assembly of strips is collectively advanced intermediate the support for the supply pack and the entrances to the strip guides, and feeding means for inducing travel movement of the assembly of strips relative to said strip assembly guide.

26. A strip separating apparatus, including a strip feeding device for feeding an assembly of superposed record strips, a guide wall over which the strips are collectively advanced from a supply pack thereof, a plurality of inclined guides arranged side by side, relative to which different strips are separately directed, and a plurality of strip receiving compartments arranged in superposed vertically spaced relation one above another to which the strips are directed, and means associated with the receiving compartments to induce zigzag folding of the strips therein.

27. A strip separating apparatus, including a strip feeding device for advancing an assembly of superposed continuous strips from a source of supply to a point of separation, a plurality of receiving compartments, guide means for

directing different strips of the assembly into different receiving compartments, and strip folding means associated with the receiving compartments for effecting automatic folding of the strips entering the compartments into independent zigzag packets.

28. In a strip separating apparatus, in combination, a plurality of gravity chutes, side by side, in which strips from an assembly pass downwardly by gravity, receiving compartments 10 with which the lower ends of certain said chutes respectively communicate so as to receive the

strips from the chutes, strip folding means for causing certain of the strips to be folded in zigzag packs in the respective receiving compartments, and a plurality of strip guides adjacent to the chute entrance passageways for guiding the strips to the latter.
